UNITED STATES PATENT OFFICE.

THOMPSON H. WILEY, OF OMAHA, NEBRASKA.

DOOR-LOCK KEEPER.

1,093,816.

Specification of Letters Patent.

Patented Apr. 21, 1914.

Application filed July 28, 1913. Serial No. 781,543.

To all whom it may concern:

Be it known that I, THOMPSON H. WILEY, a citizen of the United States, residing at Omaha, in the county of Douglas and State 5 of Nebraska, have invented certain new and useful Improvements in Door-Lock Keepers, of which the following is a specification.

This invention relates to an improved lock-keeper and has for its object to provide 10 an article of this class which may be conveniently adjusted whenever required, so that its apertures may be disposed in alignment with the longitudinally movable lock-bolt and latch-bolt of the lock.

15 It is well known that the horizontally movable latch-bolt or lock-bolt of a door will frequently make contact with the metallic parts of the lock-keeper of the door casing when an attempt is made to close or lock the 20 door, this being caused by the sagging of the house or door frame, so that the latch-bolt or lock-bolt will not be disposed in alignment and will not enter the apertures of the 25 lock-keeper, the remedy generally being to change the position of the lock upon the door or to move the lock-keeper to a higher or lower position on the door frame. These 30 changes may not be conveniently made, and when made generally result in defacement of the door or door frame. By use of the herein described invention an adjustment of the lock-keeper may be conveniently made so that the latch or bolt of the lock will be disposed in alignment with and will 35 enter the apertures of the lock-keeper.

With the foregoing objects in view, the invention presents a novel construction, combination and arrangement of parts as described herein and claimed, and as illustrated 40 in the drawing, it being understood that only one embodiment of the invention is described, and that no limitation as to form, size, proportion or minor details are 45 to be imposed within the scope of the claims.

In the drawing, Figure 1 is a vertical, front view of a keeper-plate. Fig. 2 is a view in longitudinal section of the keeper-plate. Fig. 3 is a vertical front view of the 50 adjusting-plate. Fig. 4 is a view in longitudinal section of the adjusting-plate. Fig. 5 is a front view of the device, the adjusting-plate being mounted upon the keeper-plate. Fig. 6 shows parts of a door and a door 55 frame, partly in section, the casing of the

door-lock also being in section, and the lock-keeper being in longitudinal section.

Referring now to the drawing for a more particular description, numeral 1 indicates the upright strip of a door casing having the 60 recess 2 which is usually provided for receiving therein the horizontally movable lock-bolt 3 and latch-bolt 4 of the lock 5 of the door 6.

At 7 is indicated a lock-keeper which is 65 usually set in the casing to cover recess 2, and to provide a holding means for the bolts of the lock, said lock-keeper being securely held in position by means of screws 8 which enter the door-casing.

According to the novel construction of the lock-keeper, it consists in part of a keeper-plate 9 provided midway between its ends with a comparatively large rectangular aperture 10 and with apertures 11 which 70 may be traversed by screws 8. It is also provided with grooves 12 formed on its inner side to open on its ends and upon aperture 10. A second plate is employed, this being an adjusting-plate 13. It has a length 75 less than that of plate 9 and has a width corresponding to the width of aperture 10 and grooves 12 of said plate 9. It is formed upon its outer side, midway between its ends, with a platform or stop 14 having a 80 less length than aperture 10 of plate 9, said platform having a thickness corresponding to that of said plate.

Plate 13 may be mounted in grooves 12 of plate 9, platform 14 being disposed in aperture 10, and it may have slidable movements therein, the ends *a* of platform 14 operating as stops, to limit said movements, these ends making engagements with the walls *b* of aperture 10. Said plate is provided with 85 slots 15 opening upon its ends and adapted to be traversed by screws 8. Also this plate is provided with apertures 16 and 17, these apertures being formed in platform 14.

As thus described the device may be 90 mounted in the door-casing and may be secured by screws 8; and plate 13 may be adjusted longitudinally of plate 9, so that apertures 16 and 17 will be disposed in alignment, respectively, with bolts 3 and 4. 95 It will be understood that the door, which swings horizontally, should thus present the bolts of the lock in alignment with said apertures in order that they may pass therein, and if, from shrinkage or sagging of the 100 105 110

2
door or door-casing these parts are not in alinement, the bolts will engage the metallic parts of the bolt keeper and will not work in the apertures.

5 In operation, the screws 8 may be partly raised from their seatings by well known means, and thereupon plate 13 may be adjusted longitudinally of plate 9 so that apertures 16 and 17 will be in alinement with the 10 bolts of the lock; and when members 8 are screwed home, plate 13 will be compressed against and held stationary with plate 9 by operation of the screws, and the parts will be maintained in alinement for the purposes 15 described.

Having fully described my invention, what I claim and desire to secure by Letters Patent, is—

1. In devices for the purpose described, a 20 first plate formed with an elongated aperture opening on its front and back, and having grooves formed in its back to open on its ends and on said aperture; a second plate having a greater length than the aperture of 25 the first plate and formed with attenuated end-portions having slots opening on its terminals, and provided intermediate said attenuated end-portions with an apertured platform substantially equal in thickness to 30 that of the first plate; said second plate being adapted to be mounted with its apertured platform disposed in the elongated aperture with its attenuated end-portions engaging in the grooves of said first plate; and 35 keepers traversing the grooved parts of the first plate for engagements in the slots of the second plate.

2. In devices for the purpose described, a 40 first plate formed with an elongated aperture opening on its front and back, and hav-

ing grooves formed in its back to open on said aperture; a second plate of greater length than the aperture of the first plate and having attenuated end-portions with slots formed therein, and provided intermediate 45 said attenuated end-portions with an apertured platform; said second plate being adapted to be mounted with its apertured platform disposed within said elongated aperture, the front and back surfaces of said 50 platform being substantially in alinement with the respective front and back surfaces of the first plate, its attenuated end-portions engaging the grooves of said first plate; and a keeper traversing a grooved part of the 55 first plate for engagement within a slot of the second plate.

3. In devices for the purpose described, a first plate formed with an elongated aperture opening on its front and back, and having grooves formed in its back to open on said aperture; a second plate having a greater length than the aperture of the first plate and formed with attenuated end-portions having slots formed therein, and provided intermediate 60 said attenuated end-portions with an apertured projected part; said second plate being adapted to be mounted with its projected part disposed in said elongated aperture with its attenuated end-portions engaging in the grooves of said first plate; and a keeper traversing each grooved part of the first plate for engagement in a 65 slot of the second plate.

In testimony whereof I have affixed my 70 signature in presence of two witnesses.

THOMPSON H. WILEY.
